UNITED STATES PATENT OFFICE.

WILLIAM H. KNAPP, OF BROOKLYN, NEW YORK.

DRESS-FORM.

SPECIFICATION forming part of Letters Patent No. 373,989, dated November 29, 1887.

Application filed September 26, 1887. Serial No. 250,651. (No model.)

To all whom it may concern:

Be it known that I, WILLIAM H. KNAPP, of Brooklyn, in the county of Kings and State of New York, have invented new Improvements 5 in Garment-Stands; and I do hereby declare the following, when taken in connection with the accompanying drawings and the letters of reference marked thereon, to be a full, clear, and exact description of the same, and which 10 said drawings constitute a part of this specification, and represent, in—

Figure 1, a side view of the stand complete in an expanded condition; Fig. 2, a vertical central section of the same; Fig. 3, one of the 15 ribs detached; Fig. 4, two ribs enlarged, illustrating the method of connecting the upper ends of the adjacent legs of the two ribs and also the method of tying the legs together and connecting the braces thereto; Fig. 5, a perspective view of the tie-pieces detached; Fig. 20 6, the blank from which the clip is formed; Fig. 7, a horizontal section through the clip applied to the legs, and showing the loop; Fig. 8, a vertical section through the clip, 25 showing the loop; Fig. 9, a top view of the stand, showing the series of loops with the adjusting-strap therein.

This invention relates to an improvement in that class of garment-stands which are adapted 30 to support skirts of ladies' dresses, and particularly to that class in which the stand consists of several vertical ribs around a central column, and which are made adjustable to different diameters by collars on the shaft, 35 from which braces extend to the ribs, so that by vertical adjustment of the collars the braces will be thrown outward or drawn inward, according to the direction in which the said collars are moved, the object of the invention being to construct the expandible portion 40 of the stand entirely from wire.

A represents the base upon which the stand is supported. This consists of a vertical tube with legs at its lower end, upon which it may 45 rest. Within this tube is a vertical shaft, B, supported by the tube A, but free for rotation. Near the tube A the shaft B is provided with an external screw-threaded section, C. Above the screw-threaded section C, 50 which is firmly fixed to or made a part of the

shaft B, and so as to rotate therewith, a similar screw-threaded section, D, is arranged upon the rod; but this section D is tubular, and through it the central shaft, B, extends. The upper end of the screw-threaded tubular 55 section D terminates in a suitable head, E, by which the section D may be rotated, and the shaft B extends through the head E and terminates in a similar head, F, by which the shaft B may be rotated, so that either the shaft 60 or the section D may be rotated, as occasion may require.

On the section C is an internally-screw-threaded collar, G, and on the section D is a similar screw-threaded collar, H. At the upper end of the section D is a collar, I, loosely supported upon the section D, so that the section D may be rotated without revolving the collar I; but yet the collar I is supported by a shoulder below, so as to prevent its up-and-down movement. The collars H and G are respectively adjustable vertically by means of their respective screws. Around the shaft 70 several vertical ribs are arranged, connected near their lower end by braces J with the collar G, and near their upper end are hung by braces K to the collar I, and are also connected by braces L to the collar H, the braces K and L being oppositely inclined from their point of connection with the ribs to the respective 75 collars, as clearly shown in Fig. 2.

If the shaft B be rotated in one direction, it will draw the collar G upward, or in the opposite direction will force the collar G downward, and such movement of the collar G correspondingly changes the inclination of the braces J and throws out or draws inward the ribs at the lower end accordingly as the collar is raised or lowered. The tubular screw-threaded section D being rotated, will cause 90 the collar H to rise or fall, according to the direction in which it is turned, and the braces L, being connected to the said collar, will be correspondingly moved to change their inclination with relation to the ribs, and consequently throw out or draw inward the ribs, according to the direction in which the collar H is moved, the ribs being hung by the braces K to the stationary collar I above. Broadly considered, this is a common construction and ar- 95 100

angement of parts for the adjustment of garment-stands.

The ribs are made from wire in substantially **V** shape, as represented in Fig. 3, the apex of the **V** being downward and forming the termination of the ribs at the bottom.

The legs M N of the ribs at the point where the lower braces, J, are to be connected have a short bend formed in each, as at *a*, Fig. 3, and at the point where the braces K L are to be attached near the upper end a like short bend, *d d*, is made in each leg. A series of such ribs are arranged around the standard. The upper end of one leg, M, of one rib is connected to the adjacent leg, N, by a clip, P. This holds the adjacent legs of the two ribs together, but permits the two legs of each rib to separate or be brought together as occasion may require any expansion or contraction of the stand.

Across the two legs of one rib and in the bends *a* a wire tie-piece, *e*, is applied, the two ends of the tie-piece being bent around the two legs in the said bends, so as to firmly secure the tie-piece and at the same time tie the legs together at that point. This tie-piece midway between the two legs has a short bend, *f*.

The braces J are made from wire. The inner end is bent in the form of an eye through a corresponding hole in the collar G, and the outer end is bent around the bend *f* in the tie-piece, the said bend in the tie-piece centrally locating the outer end of the brace midway between the two legs M N. At the bends *d*, near the upper end, a similar tie-piece, *g*, is applied, connecting one leg, N, of one rib with the adjacent leg, M, of the next rib. This tie-piece is made of wire bent around the respective legs in the bends *d* of the legs, so that while it ties the two legs together at that point it is, like the tie-piece *e*, prevented by the short bends from vertical movement. The tie-piece *g* has a short bend, *h*, midway between the two legs N M. The braces L are also made from wire, their inner ends bent through holes in the collar H, so as to form a hinge-eye for the brace like the inner end of the braces J, and the outer ends of the braces L are bent around the tie-piece *g* in the short bend *h*, so that the outer ends of the braces L are located midway between the adjacent legs of the two ribs.

The short bends in the tie-pieces form a pin-tle, upon which the outer ends of the braces may turn as a hinge, while the connection between the braces and the collar form hinges at their inner ends, and so that as the collars are adjusted the braces readily adapt themselves to the different inclinations to which they may be brought in the expansion or contraction of the stand.

The upper ends of the adjacent legs of the ribs, being connected by the clip P, permit the upper ends of the ribs to move outward under the action of the braces, so as to expand the extreme upper end of the stand.

It is desirable that the upper ends of the ribs may be contractible independent of the braces, because this corresponds to the waist-band of the skirt, which is variable to a different extent from that of the ribs below. To accomplish this adjustment the clips are made to not only secure the ends of the legs together, but also to form a transverse rib through which a strap may be run.

In Fig. 6 I represent the blank from which the clip P is made. This clip is in the form of a cross, cut from suitable sheet metal—as brass or tin—the length transversely being greater than the distance required between the two legs to be connected, and so as to form a flap, *i*, at each side, which may be bent around the respective legs, as seen in Fig. 7. The vertical extensions *l l* of the clip are turned inward, the one up and the other down, as seen in Fig. 8, so as to form a transverse loop, *m*, in the connection between the legs of the respective ribs. The series of loops thus formed are represented in Fig. 9. Through these loops a strap, *n*, is run and made adjustable by a buckle, *r*, or otherwise, so that by drawing upon the strap the clips and the upper ends of the ribs which they connect will be drawn inward to contract the circumference of the stand at the waist; or, if the strap be loosed, the elasticity of the wires will cause the clips to spring outward. Thus the circumference of the waist may be adjusted to any desirable extent independent of the adjustment of the ribs. By this construction the ribs, the adjusting-braces, and the connection between the braces and ribs are all made from wire; consequently cheap, no soldering is required, and consequently no liability to accidental detachment.

I claim—

1. In a garment-stand consisting of several vertical ribs surrounding a central shaft, two series of braces hung to collars on said shaft, the said collars made adjustable vertically on said shaft, each of said ribs made from wire, of **V** shape, the upper end of one leg of each rib connected to the adjacent leg of the next rib, the said legs constructed with short bends at the points where the braces are to be connected, combined with tie-pieces made from wire bent around the respective legs in said short bends, thereby connecting the said legs, the said tie-pieces constructed with a short bend midway between the respective legs, the braces also made from wire, their outer ends bent around the said tie-pieces in the short bends, and the inner ends of the braces hung to the collars on the shaft, and a series of braces hung by one end to a stationary point on the shaft, extending downward and outward, their outer ends hung to the said ribs, substantially as described.

2. A garment-stand consisting of several ribs arranged around a central shaft, the said central shaft carrying vertically - adjustable collars, the said ribs made from wire, of V shape, the upper end of one leg of each rib connected to the upper end of the adjacent leg of the next rib by a clip, P, the said clip P having its two sides closed around the said upper ends of the legs, and the said clip also constructed with flaps at the top and bottom, the said flaps turned toward each other to form loops m around the upper end of the stand,

and the adjusting - strap n, combined with braces extending from the collars on the shaft and hung to the ribs, and with braces hung by 15 their inner end to a stationary point on the shaft, extending downward and outward, hung by their outer end to the said ribs, substantially as described.
